3 Claims. (Cl. 110—8)

ABSTRACT OF THE DISCLOSURE

A domestic incinerator in which waste material is compacted into an imporous plug exposed at its bottom to the top of a combustion chamber for controlled burning of such bottom at a rate which is automatically controlled according to combustion chamber temperature by switching admission of combustion air into the combustion chamber at different burning-rate-inducing inlet locations while also providing for electrical heating of such air admitted at the inlet location having the higher burning rate inducement.

An object of the invention is to provide means to control the rate of combustion in a device where the waste material is compacted into an imporous mass and a thin layer of one face of such mass is maintained in a state of combustion.

It has been discovered that substantially fifteen hundred degrees Fahrenheit is necessary to reduce trash to a clear and odorless gas. It has further been discovered that higher temperatures render the disposal of trash more efficient and speed the operation. However, there is a limit, for such higher temperatures shorten the life of the combustion chamber and other parts of the apparatus. Moreover the higher temperatures result in the formation of slag which, if present in sufficient quantities, tends to clog the combustion chamber, whereas somewhat lower temperatures produce brittle matter which can be easily cleaned out. It is therefore important that a suitable temperature be set and closely maintained, a temperature that will produce as high a speed of operation as possible without reaching the point where destruction and clogging of the apparatus takes place.

In accordance with the present invention electrical means are employed to induce combustion and a supply of air for maintaining combustion is fed into the combustion chamber. It has been found that combustion of the burning face of the plug of compacted material will take place with a higher intensity when the air for combustion is brought in closer to the burning face than when it is brought in at a distance therefrom.

It is to be noted that at the temperature at which the combustion chamber is operated heat is transmitted inside the chamber by radiation so that the chamber and the burning face of the plug are all at about the same temperature. The higher the velocity of the combustion air over this hot face of the plug the higher the rate of combustion of carbon at the face. Since the quantity of combustion air remains approximately the same and since the conduction losses through the chamber wall remain the same, the temperature will rise when the combustion rate increases.

Accordingly, a temperature probe is employed to sense the temperature of the combustion chamber. When the temperature falls below the predetermined point, this device will control an air valve to direct the incoming air for combustion nearer the burning face of the plug, thereby increasing the air velocity and the combustion rate and therefore causing the temperature to rise to a predetermined level. Alternatively, when the temperature rises above this predetermined level, the air valve will be oper-

2

ated to direct the air for combustion further away from the burning face.

A feature of the invention is the combination of a temperature probe operating an electrical contact, a solenoid 5 operated air valve and alternative air ducts controlled thereby, one for delivering air for combustion near the burning face of the plug and the other for delivering such air at a distance therefrom.

Another feature of the invention resides in the provision 10 of means to preheat the air supply when it is to be delivered substantially at the face of the plug, and to omit such preheating means when the air supply is to be delivered at a distance therefrom. It will be understood that the electrical means used to induce combustion is not necessarily in continuous operation, even though the combustion air is flowing in contact therewith, and that the combustion of the face of the plug of compacted material is sufficient without preheat for longer or shorter periods to maintain combustion. The electrical heaters are used 15 primarily during start ups and periods when wet materials are being burned. The heaters are controlled by a separate probe, and cutoff of electric heat occurs at a temperature about 100° F. lower than the temperature at which air switching occurs.

Another feature of the invention is the provision of 20 an air preheating chamber constructed in the line of the first duct used for delivering the combustion air substantially to the face of the burning plug. By the use of such a chamber the air delivered to the face of the imporous plug may be sufficiently high in temperature to induce 25 combustion thereof and during operation sufficiently high in temperature to supply the additional heat required to maintain the chamber temperature when burning a wet load. Generally, the walls of the combustion chamber are 30 constructed of ceramic material and this air preheating chamber is fashioned within the mass of such ceramic material and is thus heat insulated from the outer surfaces of the device both for safety and efficiency.

Other features of the present device are disclosed in 35 applications Ser. No. 329,044, filed Dec. 9, 1963 by Franklin S. Malick, now Patent No. 3,313,253, and Ser. No. 347,886, filed Feb. 27, 1964 by Bernard Miller, which are herein considered prior art disclosures and which are introduced herein and made a part hereof.

Another application Ser. No. 501,546, filed on even 40 date herewith in the name of Summer F. Wiley, Jr. discloses a means of the same nature as that herein disclosed, but adjusted to operate so as to establish and maintain a specific temperature suitable for the destruction of tin cans.

Other features will appear hereinafter.

The drawings consist of a single sheet having a single 45 figure in the form of a schematic representation of an incinerator partly in cross section showing the various components of the device and the relation of such components one to the other.

The device consists substantially of a metal trash bin 1, having an air tight lid 2, provided with a conventional compressed air inlet 3. A trash-compacting means 50 in form of a bag 4 is arranged to be inflated by the compressed air from the inlet 3 so that trash 5 may be compressed into an imporous mass and forced downwardly until its lower face lodges at a given level herein, by way of example, fixed by a set of grate bars 6. This lower face then substantially becomes one wall of a combustion chamber 7 so that this lower face may be said to be maintained at the junction of the combustion chamber and the trash bin. The combustion chamber is surrounded 55 by heat insulation 8 which may be ceramic material.

A chamber 9, also covered by this ceramic material, houses an electrical resistance heater 10, so that air from

the supply pipe 11, switched by the selector valve 12 into a first duct 13, may be heated and then passed through a manifold 14 and air distribution means 15 in the form of pipes provided with a plurality of orifices to project jets upwardly toward the face of the plug of compacted material. By this means combustion of the face may be induced and maintained.

A conventional temperature probe 16 protrudes into the combustion chamber 7 and controls a conventional electrical switch 17 which in turn controls a solenoid valve actuator 18. By this means, when the temperature in the combustion exceeds a predetermined point, the valve 12 may be operated to divert the air supply in the inlet 11 into a second duct 19, supplying a region of the combustion chamber 7 remote from the burning plug surface via an outer annular chamber 20 and radial ports 21, so that now the air for maintaining combustion is introduced at a distance from the face of the plug of oxidizable material 5. A second probe (not shown) controlling a second switch (not shown) can be employed for turning on and off the heaters 10, or the probe 16 and switch 17 may serve such function, as shown in the drawing.

The air supply for combustion may be supplied under pressure through the pipe 11 or the same effect may be produced by suction means provided in the exhaust 22 exiting from annular chamber 20, or both such means may be provided.

Various practical embodiments of this scheme may be provided, but all such embodiments will contain one or more probes to sense the temperature in the combustion chamber, which will operate either to supply air for combustion substantially at the face of the plug, or, alternatively, to supply combustion air to another point in the combustion chamber at a distance from such face, and to preheat the air supplied adjacent the face of the plug, when necessary to maintain suitable combustion.

The trash bin is air tight so that combustion of only a thin layer of the face of the plug of compacted imporous material takes place and, through the switching back and forth of the air valve 12 under control of the probe 16 on either side of the predetermined fixed temperature value, this value is substantially maintained.

What is claimed is:

1. In an incinerator device having a combustion chamber (7) surmounted by a trash bin (1), and means (4, 6) in the trash bin for compacting trash (5) therein into an imporous plug of oxidizable material with its bottom face constituting an upper wall of the combustion chamber:

- (a) an air supply pipe (11),
- (b) first air conveying means (13, 9, 14, 15) for delivering air into the top of the combustion chamber (7) onto the bottom face of the plug of trash (5) to increase rate of burning thereof,
- (c) second air conveying means (19, 20, 21) for delivering air into the bottom of the combustion chamber (7) to decrease rate of burning of the bottom of the plug of trash (5), and
- (d) air switching means (12, 18, 17, 16) including a selector valve (12) and temperature-responsive actuator means (16, 17, 18) therefor operative to open one or the other of the first and second air conveying means to the air supply pipe (11) according to temperature changes in the combustion chamber (7).

2. The incinerator device of claim 1, further comprising:

- (e) air heating means (10, 17, 16) including an electrical resistance heater (10) and temperature-responsive control means (16, 17) therefor operative to heat the air passing through said first air conveying means (13, 9, 14, 15) according to the temperature in the combustion chamber (7).

3. The incinerator device of claim 2, wherein the temperature-responsive actuator means (16, 17, 18) comprises a solenoid (18) for operating the selector valve (12), and the temperature-responsive control means (16, 17) for the resistance heater (10) as a means for controlling such solenoid.
